UNITED STATES PATENT OFFICE.

JOHN S. BARNES, OF ANN ARBOR, MICHIGAN, ASSIGNOR TO WIRE PRODUCTS CORPORATION, A CORPORATION OF MICHIGAN.

WIRE LOOM.

Application filed January 12, 1923. Serial No. 612,281.

To all whom it may concern:

Be it known that I, JOHN S. BARNES, citizen of the United States, residing at Ann Arbor, county of Washtenaw, State of Michigan, have invented a certain new and useful Improvement in Wire Looms, and declare the following to be a full, clear, and exact description of the same, such as will enable others skilled in the art to which it pertains to make and use the same, reference being had to the accompanying drawings, which form a part of this specification.

My invention relates to an improvement in wire looms shown in the accompanying drawings and more particularly described in the following specification and claims.

The primary object of this invention is to provide a simple and effective loom for the manufacture of wire fence whereby all the lateral wires are brought under the same relative tension so that the pickets inserted between their twisted strands may be straight, vertical and regular in appearance,—that the lateral wires may be under uniform tension when attached to the posts.

In Patent No. 798,154, issued to me August 24th, 1905, for fence looms is shown a wire fabric delivery mechanism consisting of a plurality of notched wheels,—mounted upon a single shaft,—corresponding in number to the respective lateral wires of the finished fence fabric. The notches in these several wheels receive the respective pickets of the fence fabric and through the operation of suitable driving mechanism, including a ratchet gear-wheel and a co-operating pair of engaging dogs,—draws the finished fabric forward as rapidly as it leaves the twisting members, for delivery to the winding drum. It has been found in practice however that the use of a single row of notched wheels,—driven by a ratchet gear-wheel in turn actuated by alternatingly engaging dogs,—fails to provide a uniform tension of the respective line or lateral wires;—there being considerable "backlash" due to the alternate engaging and disengaging of the respective dogs and to the fact that an insufficient number of the pickets are simultaneously engaged by the notched wheels to insure a positive forward movement of the several lateral wires under uniform tension. It is therefore one of the objects of the present invention to overcome these objections by providing a plural num-

ber of feed-drums fitted with a plurality of notched bars adapted to receive all the lateral wires of the fence and to engage the several pickets,—each of the bars being provided with a sufficient number of notches to adapt it for any special spacing of the lateral or line wires of the fence desired,—the arrangement being such that a relatively greater number of the pickets of a completed fence may be engaged than was possible with my former device;—the feed drums being driven by a worm gear to insure a positive forward movement of the drums and to avoid any backlash of the latter.

A further object of the invention consists in the means employed for shaping each end of the picket that it may be given an arched form whereby the finished fence product may comprise a plurality of interlaced arched pickets at the top and bottom of the fence.

A further advantage of this construction is that it is thus possible to divide the finished product longitudinally to provide a fabric having a single arched or finished edge, the capacity of the machine is thus doubled for a given period of operation.

A further object of the invention is to provide means for regulating the tension of each pair of strands forming the line or lateral wires of the fence as they pass from the wire spools to the testing gears.

A further object of the invention is to provide means for automatically forcing the end of the return bend of the pickets into the crotch formed by twisting together each pair of the strands forming the line wires of the fence.

A further object of the invention consists in the clutch mechanism and co-operating means employed to throw the machine into and out of operative condition.

A further object of the invention consists in means for automatically decreasing the speed of the winding drum in direct ratio to the increasing diameter of the wire fabric bundled thereon, with correspondingly increasing driving power.

With the foregoing and other objects in view which will appear as the description proceeds the invention further resides in the combination and arrangement of parts and in the details of construction hereinafter described and claimed it being understood that changes may be made in the precise embodi-

ment of the invention without departing from the spirit of the same.

In the drawings accompanying this specification:

5 Figure 1 is a side elevation of a wire loom embodying my invention.

Figure 2 is a plan view of the loom with parts broken away.

10 Figure 3 is a fragmentary elevation of the opposite side of the loom shown in Figure 1, with the picket trough removed but shown in dotted lines.

15 Figure 4 is an end elevation of the loom with the wire spool rack removed,—looking toward the end of the twisting gears.

Figure 5 is a perspective view of a detail showing the means employed to form a loop at the ends of the pickets while weaving the latter into a fence.

20 Figure 6 is an elevation partly in section of the detail indicated in Figure 5 showing a movable platen provided with a plurality of downwardly extending pins of different lengths adapted to successively enter apertures in a stationary table below the platen, whereby the ends of the picket are held between the pins and are gradually given an arc-shaped form,—the ends of the pickets being engaged between the twisted strands of 30 the line wires as the fence is constructed.

Figure 7 is a similar view taken on or about line VII—VII of Figure 6 showing a fragment of the fence resting upon the supporting table with the ends of two pickets as they would appear before being given an arc-shaped formation by the downward thrust of the depending pins carried by the movable platen.

40 Figure 8 is a similar view showing the pins intersected by line VIII—VIII of Figure 6 entering the apertures in the supporting table,—whereby the first step is taken to give the ends of the pickets an arc-shaped formation.

45 Figure 9 is a similar view showing the pins intersected by the line IX—IX in Figure 6 as they would appear upon entering the sockets in the supporting table showing the next successive step in forming the arc-shaped ends of the picket.

50 Figure 10 is a similar view showing the pins intersected by the line X—X in Figure 6 entering the sockets in the supporting table and showing the next successive step in forming the arc-shaped ends of the picket.

55 Figure 11 is a similar view showing the pins intersected by the line XI—XI in Figure 6 as they would appear upon entering the sockets in the stationary table showing the next step taken in forming the arc-shaped ends of the picket.

60 Figure 12 is a similar view showing the pins intersected by the line XII—XII in Figure 6 as they would appear upon entering the sockets in the stationary table and

indicating the next successive step in forming the arc-shaped ends of the picket.

Figure 13 is a similar view taken on or about line XIII—XIII of Figure 6 showing the pins as they would appear upon entering the sockets in the table below, being the next step taken in forming the arc-shaped end of the picket.

Figure 14 is a vertical sectional view through the device shown in Figure 5 taken on or about line 14—14 of Figure 7.

Figure 15 is a fragmentary detail of the product of the wire loom.

Figure 16 is a perspective view of a detail of construction embodying a device adapted to maintain the wire under tension as it is delivered from the wire spools to the twisting gears.

Figure 17 is a perspective view of a detail of construction embodying one of the devices employed to give the ends of the pickets an arc-shaped formation, showing also the means for beating the arc-shaped end of the picket into the crotch formed by the twisted strands of the lateral wires and also a fragmentary detail of one of the twisting members whereby the lateral wires are twisted together to engage and support the pickets.

Figure 18 is a longitudinal vertical sectional view through one of the lateral wire twisting members, adjustably mounted upon a pair of transverse rails secured to the frame of the loom.

Figure 19 is a fragmentary end elevation of a detail of construction embodying the clutch mechanism controlling the operation of the tension drums.

Figure 20 is a fragmentary elevation with the parts in section of the detail shown in Figure 19 taken at right-angles to the latter.

Figure 21 is a fragmentary view of the detail shown in Figures 19 and 20.

Referring now to the letters of reference placed upon the drawings:

Mounted upon the inclined rails A, secured to the frame B of the machine are a plurality of wire spools C, from which strand wires 1 and 2 are led in pairs through a plurality of spring tension devices D—a detail description of which will follow—to a plurality of wire twisting members E,—which will also be hereafter described in detail,—adapted to twist the strands of wire together to form lateral cables between and around the pickets L of the fence.

A pulley F mounted upon a shaft F¹ is supported in suitable hangers F² bolted to the frame of the machine. The pulley F is provided with a clutch mechanism F^a adapted to engage the co-acting members G^a of the clutch carried by a driving pinion G keyed to the shaft F¹. F^b is a spring to

maintain the pulley in driving relation with the pinion.

H is a gear mounted upon a shaft H^a supported in suitable bearings attached to the frame of the machine—see Figure 1. Projecting from the face of the gear are wedge-shaped cams H^b, H^c, co-operating with the wedge-shaped portion I^a, of the clutch releasing member I, sleeved upon a hub of the driving pulley to periodically release the driving connection between the pulley and driving pinion G.

A link bar J pivotally connected to the gear H and to a lug K^a extending downwardly from the rack bar K serves to reciprocate the rack bar which thereby actuates the wire twisting elements E, shown in detail in Figures 17 and 18 of the drawings.

The wire twisting device E is adjustably mounted upon a pair of transverse bars 3, 3, bolted to the main frame of the loom by a bolt 4 extending through a plate 5 beneath the bars into the pedestal 6 of the twisting device. The pedestal is slotted for the passage of the rack bar K and journaled in the pedestal above the rack bar is a rocking element 7, having oppositely disposed longitudinal peripheral grooves 8 for the passage of the respective strands 1 and 2 of the lateral cables. The rocking element 7 is also provided with a transverse hole and open slot, as indicated at 9, to admit the entry and delivery of the pickets L between the strands of the cable,—see Figure 17 of the drawings. Pinned to the rocking element 7 is a pinion M in mesh with the rack bar K and actuated by the alternate movement of the latter, thereby rocking the element 7, to twist the strands of wire together in alternate directions between the respective pickets as the fence fabric is thus formed.

Upon the strands of wire being twisted together corresponding with the desired spacing of the pickets and determined by the travel of the rack bar K in one direction—the cam member H^b of the gear H will be in position to act upon the co-operating wedge shaped portion I^a of the clutch releasing member I, thereby disengaging the driving pinion G from operative connection with the driving pulley, whereby the operation of the wire twisting elements E is suspended to admit the manual insertion of a picket L between the strands 1 and 2 of the respective cables.

Bolted to the frame of the loom is a trough L^a for supporting a plurality of pickets prior to guiding them between the line wires or lateral cables of the fence. Adjacent to the body of the trough and forming a part thereof is a narrow V-shaped channel L^b to receive and guide a single picket between the feed rolls L^c and L^d, journaled in the upstanding bracket L^e bolted to the frame of the machine. L^f is

a driving pulley secured to the shaft of the feed roll L^d to provide an independent driving means for operating said feed rolls whereby the pickets are delivered between the strands of the lateral cables. L¹ is a manually operated bell-crank lever pivoted to a bracket L² secured to the picket trough L^a, adapted to engage the end of a picket to deliver the latter between the feed rolls L^c and L^d.

Journalized in overhanging brackets 8^a bolted to the frame of the loom is a transverse shaft 9^a to which are secured a plurality of swinging arms 10, longitudinally adjustable upon the shaft. Pivoted to the end of the movable arms 10 is a swinging jaw 11 having a rocking arm to which is pivoted a link bar 12 fitted with a hub 13 loosely sleeved upon a transverse shaft 14 supported in the overhanging brackets 8^a, 8^b, adjacent to the shaft 9^a.

Located on each side of the loom are picket bending devices N, N, linked together that they may operate simultaneously, adapted when operated to bend each end of the pickets that the finished fabric may present arched interlacing loops at each side thereof—as shown in Figure 15. Each of these picket bending devices comprise a platform N¹ having downwardly projecting lugs through which extend shafts N² carried by supporting brackets N³ attached to the frame of the machine—the platform having a limited longitudinal slidable movement upon the shafts. N^a is a vertically movable superimposed platform slidable upon guides N^b, N^b, projecting upwardly from the platforms N¹. N^c is a fitting secured to the guides N^b, from which extends a link bar N^d connected with a similar fitting carried by the picket bending device on the opposite side of the machine. Secured to and projecting downwardly from the movable platform N^a are a plurality of pins N^e of relatively different length having wedge or beveled shaped ends N^f adapted to bear against the ends of the pickets to gradually bend the latter into an arch-shaped form;—the pins projecting through apertures in the platform N¹ beneath. Spaced from and parallel with the beveled end pins N^e are a plurality of pins P projecting downwardly from the movable platform which also when actuated extend into a plurality of apertures in the platform below.

Q is a manually operated bell-crank lever pivoted to a lateral extension of the fitting N^c and is connected by a link Q¹ with the movable platform. Q² is a link-bar connecting the bell-crank lever Q with a bell-crank lever Q³, pivoted to the movable platform of the picket bending device on the opposite side of the loom. The bell-crank lever however in the latter case is relatively

- short due to the fact that both devices are simultaneously operated by the manually operated bell-crank lever Q —see Figure 4. Q^4 is a spring connected with the lever Q and link bar Q^2 to return the parts to their normal position when released from manual control.
- R is a bracket carried by the shafts 9^a and 14, to which is pivoted a bell-crank lever R^1 , connected by a link R^2 with one of the swinging arms 10 secured to the shaft 9^a. R^3 is a link connecting the other arm of the bell-crank lever R^1 with a fitting R^4 secured in a slotted way q in the link bar 15 Q^2 whereby the throw of the swinging arm 10 may be adjusted so that upon the manual operation of the lever Q the respective swinging arms 10 secured to the shaft 9^a may force the picket out of the slotted end 20 of the twisting device E , into the crotch formed by the twisted strands 1 and 2 of the lateral cable. Upon the release of the manually operated lever Q the spring Q^4 will return the swinging arms 10 back to their 25 normal position in alignment with the feed rolls M , M^1 and transverse hole and slot 9, in the rocking elements of the twisting device. When thus aligned the jaws at the lower end of the swinging arms are closed 30 to guide the pickets upon leaving the feed rolls through the transverse holes 9 in the respective twisting devices—see Figure 17. S is a pinion in mesh with the gear H mounted upon a shaft S^1 journaled in bearings S^2 , S^3 , bolted to the frame of the loom. S^a is a worm gear on the shaft S^1 in mesh with a worm gear S^b mounted upon a transverse shaft S^c journaled in the frame of the machine. S^d is a spur gear on the shaft S^c 35 40 in mesh with the like spur gear T on the shaft T^1 journaled in brackets secured to the frame of the machine.
- U is a drum on the shaft S^c provided with a plurality of ribs U^1 notched as at U^2 to receive the lateral wires or cables of the fence fabric. U^3 is a similar drum carried by the shaft T^1 also fitted with notched ribs to receive the lateral wires of the fence 45 fabric.
- 50 Mounted on the end of the shaft T^1 of the drum U^3 is a bevel-gear V in mesh with a like bevel-gear V^1 keyed to a partially screw-threaded shaft V^2 supported at one end in a fitting V^a and at its opposite end in a fitting V^b , carried by a shaft W on which is mounted a wind-up drum W^1 .
- 55 Projecting from the fittings V^a and V^b are arms V^c for supporting a guide rod V^d . Mounted upon the guide rod V^d and slidable thereon is a member X , having a divided hinged arm X^1 , adapted to embrace the threaded portion of the shaft V^2 , which it is tapped to receive. X^2 is a wing-nut to secure the divided hinged arm together that 60 it may engage and travel along the threaded

portion of the shaft V^2 when the latter is rotated by the operation of the beveled gears V and V^1 .

Y denotes a friction disc keyed to and longitudinally slidable upon the unthreaded portion of the shaft V^2 ;—the forked arm of the member X engaging a flanged hub integral with the friction disc. Z is a friction disc mounted upon the shaft W of the wind-up drum driven by the friction disc Y on the shaft V^2 .

The wire fence fabric having been engaged by the notched ribs carried by the feed drums U and U^3 the fabric is drawn from the twisting mechanism and delivered to the wind-up drum W^1 upon which it is wound through the operation of the friction disc;—it being apparent that as the diameter of the roll of finished fabric increases upon the wind-up drum the driving speed of the latter will be decreased with a corresponding increasing power due to the disc Y being automatically shifted toward the periphery of the friction disc Z , as a result of the member X traveling upon the threaded shaft V^2 . The distance traveled by the member X upon the threaded shaft is predetermined and corresponds to the predetermined diameter,—or the length of the finished wire fabric upon the winding drum. Upon the roll being completed it is removed and the end of the next section of wire fabric is engaged to the roll or winding drum;—the wing-nut X^2 is then adjusted to release the divided hinged arm that the member X may be shifted along the screw threaded shaft in order that the friction disc Y may be returned to its initial position upon the friction driven disc Z .

Referring again to the spring tension device D which receives the wire strands 1 and 2,—forming the lateral cables of the fence—from the spools C as they are led to the twisting members E : A rocking arm D^1 is pivoted in a U -shaped frame D^2 secured to the frame of the loom;—mounted in the rocking arm D^1 is a roller D^2 provided with peripheral grooves d , d , to receive the wire strands. Co-operating with the roller D^2 is a similar roller D^3 journaled in the U -shaped frame, and suspended from the end of the rocking arm is a bolt D^c fitted with a wing-nut D^b ,—to which is connected a spring D^d secured to the frame of the loom.

By adjusting the wing-nut the spring may be regulated thereby increasing the tension of the device upon the strands of wire forming the lateral cables, thus overcoming any “slack” in the wire that might otherwise obtain.

Having now indicated the several parts by reference characters the construction and operation of the loom will be readily understood.

It will first be assumed that spools of

105

110

115

120

125

130

wire for forming the twisted lateral cables of the fence fabric have been installed upon the inclined rails A of the loom and that the wires have been led in pairs through 5 the respective tension devices D,—through the twisting member E,—the feed drums,—to the wind-up drum to which they are secured.

Power having been applied to the driving 10 pulley F the gear H is actuated by the driving pinion G, the link connection J between the gear H and rack bar K thereby operates the latter rotating the twisting members E a predetermined number of times governed 15 by the travel of the rack bar in one direction.

The rack bar having reached the end of its movement, one of the cams H^b on the gear H will be in position to operate the 20 clutch releasing member I thereby suspending movement of the rack bar in the opposite direction until the clutch F^a and G^a are again engaged.

A picket is now inserted in the trough L^b 25 and is manually forced between the feed rolls L^c and L^d by the bell-crank lever L¹. The feed rolls being independently driven by the driving pulley L^f the picket is fed forward through the eyes formed by the 30 closed jaws of the swinging arms 10, which serve to guide the picket through the slotted transverse holes 9 of the several twisting members E and between the strands of the several lateral wires forming the fence 35 fabric.

The ends of the picket being now at rest upon the platform N¹, N¹, of the picket bending devices N,—see Figures 5 and 7,—the lever Q is operated and through its link 40 connections simultaneously actuates the respective vertically movable superimposed platforms N^a, N^a, carrying the groups of pins P and N^e. The pins N^e being of relatively different lengths and wedge shaped at their lower ends N^f they successively bear against 45 the picket as they are forced down causing the picket to assume the arc formed by the several guide pins P, as clearly indicated in the successive steps taken in forming the pickets,—see Figures 7 to 13.

The manual operation of the lever Q also rocks the respective arms 10 thereby forcing the picket inserted through the twisting members E out of their slotted jaws and 55 against the free ends of the preceding picket when the latter is in the position shown in Figure 13. This action drives the partially completed arced end of the pickets,—together with the last added picket,—into the crotch formed by the strands 1 and 2 of the respective lateral cables, thereby completing the formation of the arced ends of the picket previously inserted.

Upon swinging the rocking arms 10 to 60 force the picket out of the twisting members

into the crotch formed by the strands of the lateral cables, the clutch releasing member I, by its link connection I¹, I², I³, with the clevis I⁴ on an arm integral with the movable platform N^a, causes the clutch releasing member I to rock sufficiently to release the clutch member G^a that it may again engage the clutch F^a through the action of the spring F^b, thereby forcing the driving pulley into operative driving relation with the gear H,—the movement of the rack bar being in a reverse direction and thus reversing the rotation of the twisting elements, that the wire strands may be twisted in an opposite direction between alternating 80 pickets.

The arc-shaped ends of the pickets are confined between the pins P and N^e of the twisting devices when the latter is depressed by the operation of the lever Q while twisting the strands of the lateral cables together. The twisting devices are drawn along with the fence fabric—a distance equivalent to the space between pickets governed by the travel of the rack bar K in one direction. 90 Upon the movement of the rack bar being suspended by the operation of the clutch releasing member I—as previously explained—the lever Q is then released from manual control whereupon the spring Q⁴ 95 acting upon the lever Q raises the vertically movable platen N^a to its initial position, thus withdrawing the pins P and N^e from engagement with the arc-shaped ends of the picket.

Upon the pins of the twisting device being raised from engagement with the arc-shaped ends of the picket, the spring N⁴ on the shaft N² becomes operative to shift the picket bending devices N, N, to its initial position,—the link I³ being free to slide upon the pin of the clevis I⁴,—to receive the picket to be next inserted whereupon the operation just described is repeated.

The strands forming the lateral cables as previously stated are twisted in opposite directions between alternate pickets,—the distance between the pickets being governed by the travel of the rack bar in one direction and thus actuates the several twisting members in opposite directions between alternate pickets.

As the wire fabric is formed the pickets will be engaged by the projecting ribs U¹ of the drums U and U³ driven by the worm-gears S^a and S^b and respectively co-operating to insure a positive forward feed or movement of the wire fabric to the bundling drum without danger of backlash or slack.

The bundling drum is actuated by the friction disc Z driven by the friction disc Y mounted and longitudinally slidably upon the screw threaded shaft V², which is in turn actuated by the bevel gears V and V¹.

The friction disc Y is automatically shifted toward the periphery of the disc Z,—as the fabric is wound upon the bundling drum,—by the yoke X, one arm of which engages 5 a flange on the hub of the friction disc Y, the other arm of the yoke engaging a threaded portion of the shaft V².

It will now be obvious that upon the shaft V² being rotated by the bevel gear V¹ and 10 V², the yoke X will be forced to travel along the screw threaded shaft carrying with it the frictional driving disc Y until the latter reaches the peripheral margin of the driving disc Z—as indicated in dotted lines 15 in Figure 3. The travel of the disc Y toward the periphery of the driven disc Z is timed so that upon reaching the marginal edge of the latter a roll of wire fabric of standard length will be wound upon the 20 bundling drum from which it may then be removed. The frictional driving disc Y is then returned to its initial position—as indicated in Figure 3—by releasing the wing-nut X² so that the divided arm X¹ of the 25 yoke X may be opened sufficiently to permit the latter to slide back over the threaded portion of the shaft V² to its initial position. The wing-nut X² is then again adjusted so that the tapped portion of the 30 yoke arm will engage the threaded portion of the shaft.

The wire strands 1 and 2 as they leave the wire spools to be delivered to the twisting members are held under suitable tension by 35 the tension devices D—the construction and operation of which has been previously described.

Having thus described my invention what I claim is:

40 1. In a wire fence machine, a plurality of twisting members adapted to twist wire strands together to form the lateral cables of a fence, means for feeding wire pickets between the strands of the lateral cables, 45 means for looping the ends of the pickets including spaced perforated platforms, a vertically movable platen above each platform provided each with a plurality of downwardly directed pins of different length adapted to enter the perforations of 50 the respective platforms, each platform having a plurality of upwardly directed guide pins, and means for actuating the platens to cause the pins thereof to engage and loop 55 the ends of the pickets.

2. In a wire fence machine, a plurality of twisting members adapted to twist wire strands together to form the lateral cables of a fence, means for feeding wire pickets 60 between the strands of the lateral cables, means for looping the ends of the pickets including spaced perforated platforms, a vertically movable platen above each platform provided each with a plurality of downwardly directed pins of different 65

length adapted to enter the perforations of the respective platforms, each platform having a plurality of upwardly directed guide pins, means for actuating the platens to cause the pins thereof to engage and loop the ends of the pickets, and means for withdrawing the picket looping means from the 70 looped ends of the pickets.

3. In a wire fence machine, a plurality of twisting members adapted to twist wire strands together to form the lateral cables of a fence, means for feeding wire pickets between the lateral cables, means for looping the ends of the pickets including 80 spaced, movable, perforated platforms, a vertically movable platen above each platform provided each with a plurality of downwardly directed pins of different length adapted to enter the perforations of the respective platforms, each movable platform having a plurality of upwardly directed guide pins and means for actuating the platens to cause the pins thereof to enter the perforations of the respective platforms and to engage and loop the ends of 85 the pickets.

4. In a wire fence machine, a plurality of twisting members adapted to twist wire strands together to form the lateral cables of a fence, means for feeding wire pickets between the lateral cables, means for looping the ends of the pickets including spaced, movable, perforated platforms, a vertically movable platen above each platform provided each with a plurality of downwardly directed pins of different length adapted to enter the perforations of the respective platforms, each movable platform having a plurality of upwardly directed guide pins, 90 means for actuating the platens to cause the pins thereof to enter the perforations of the respective platforms and to engage and loop the ends of the pickets.

5. In a wire fence machine, a plurality of twisting members adapted to twist wire strands together to form the lateral cables of a fence, means for feeding the wire pickets between the strands of the lateral cables, 95 means for forcing each picket into the crotches formed by the strands of the lateral wires, means for automatically looping an end of each picket including a perforated platform, a vertically movable platen above 100 said platform and provided with a plurality of downwardly directed pins of different length adapted to enter the perforations of said platform, the platform having a plurality of upwardly directed guide pins, means for actuating the platen to cause the pins thereof to enter the perforations of the 105 platform and in their passage to said 110

115 platform and in their passage to said 120 platform and in their passage to said 125 platform and in their passage to said 130 platform and in their passage to said

forations engage the ends of the pickets and means for withdrawing the platen from cooperative relation with the platform and with the fence material.

- 5 6. In a wire fence machine, a plurality of spools to receive strands of wire, a reciprocating rack-bar, a plurality of wire twisting devices simultaneously actuated by the rack-bar for forming the lateral cables of the fence fabric, means for automatically arresting the movement of said twisting means at the end of each stroke of the rack-bar, said means including a clutch mechanism, means for inserting a picket between the strands of wire following the suspended rotation of said twisting means, means including a plurality of rocking members adapted to force the inserted picket into the crotch formed by the strands of the respective lateral cables, means for actuating the clutch releasing mechanism, whereby the twisting means may be again actuated, means including a plurality of feed drums provided with projecting lugs adapted to engage the respective pickets of the finished fabric as the latter leaves the twisting means, means including a worm gear mechanism for actuating said feed drums and means for bundling the wire fabric upon leaving the feed drums.

7. In a wire fence machine, a frame, a plurality of rotatable elements provided with longitudinal passages for the wire strands forming the lateral cables of the fence, and provided with a transverse hole and slot at one end for the passage of the pickets, a pinion keyed to each of the rotatable elements, a rack-bar in mesh with said pinions, means for reciprocating the rack-bar, a rock shaft mounted in the main frame above said pinions, a plurality of arms depending from said rock-shaft and keyed thereto to rock therewith, a swinging jaw pivoted to the free end of each of the rocking arms, a shaft journalled in the frame adjacent to the rock shaft, a link pivoted to each of the swinging jaws and to said second mentioned shaft whereby the swinging jaws may be automatically closed to guide the picket and afterwards opened to release the picket simultaneously with the operation of the rock shaft, and means for actuating the rock shaft.

8. In a wire fence machine, a plurality of twisting members adapted to twist wire strands together to form the lateral cables of a fence, means for feeding the wire pickets between the strands of the lateral cables, means for automatically looping the ends of the pickets including spaced perforated platforms, a vertically movable platen above each platform provided each with a plurality of downwardly directed pins of relatively different length bevelled at their lower ends and arranged in the arc of a circle

adapted to enter the perforations in the platform below, each platform having a plurality of upwardly directed guide pins, and means for actuating the platens to cause the pins thereof to enter the perforations of the respective platforms and in their passage to said perforations engage the ends of the pickets to thereby loop the ends of the pickets.

9. In a wire fence machine, a plurality of twisting members adapted to twist wire strands together to form the lateral cables of a fence, means for feeding the wire pickets between the strands of the lateral cables, means for automatically looping the end of the picket including a perforated platform having a limited longitudinal movement in line with the travel of the fence fabric, a vertically movable platen provided with a plurality of downwardly directed pins of relatively different length bevelled at their lower ends and arranged in the arc of a circle, adapted to enter the perforations in the platform below, said movable platen being also provided with a plurality of guide pins spaced from the first named pins whereby the end of the picket may enter between the respective rows of pins, means for actuating said movable platen whereby the bevelled ends of the pins of relatively different length may successively act upon the end of the wire picket to force it to conform to the arc of a circle described by the guide pins, means for forcing the picket when delivered from the twisting means into the crotch formed by the strands of the lateral wires, means for withdrawing the picket looping means from the looped end of the picket, means for returning the said picket looping means to its initial position to receive the next picket and means for reversing the movement of the twisting means whereby the strands of wire may be twisted in opposite directions between alternate pickets.

10. In a wire fence machine, including means for twisting a plurality of pairs of wire strands together between adjacent pickets to form the lateral cables of a fence, means for looping the ends of the pickets to form a finished edge for the wire fabric, said means being adapted to travel with the wire fabric a distance substantially corresponding with the predetermined distance between pickets, said looping means including a platform adapted to support the end of the picket, a vertically movable platen fitted with a plurality of pins of relatively different length having bevelled ends to successively engage and bear against the picket, whereby the latter may be gradually bent to the arc of a circle, means for actuating said movable platen, means for automatically returning the movable platen to its initial position, whereby the picket is released from said looping means, and means for return-

ing the looping means to its initial position whereby it may receive and act upon the next inserted picket.

11. In a wire fence machine, a plurality of twisting members adapted to twist wire strands together to form the lateral cables of a fence, means for feeding the wire pickets between the strands of the lateral cables, means for automatically looping the end of the picket including a perforated platform having limited movement, a vertically movable platen provided with a plurality of downwardly directed pins of relatively different length, arranged in the arc of a circle adapted to enter the perforations in the platform below; said movable platform being provided with a plurality of upwardly directed guide pins, means for actuating said movable platen whereby the ends of the pins of relatively different length successively act upon the end of the wire picket to force it to conform to the arc of a circle, and means for withdrawing the platen from cooperative relation with the platform.
12. In a wire fence machine, including means for twisting a plurality of pairs of wire strands together between adjacent pickets to form the lateral cables of a fence, means for looping the ends of the pickets to form a finished edge to the wire fabric, said looping means including a platform adapted to support the end of the picket, a vertically movable platen provided with a plurality of downwardly directed pins of relatively different length to successively engage and bear against the picket, whereby to bend the end of the picket on the arc of a circle, means for actuating the platen, means whereby the picket is released from said looping means, and means for returning the looping means to its initial position whereby it may receive and act upon the next inserted picket.

13. In a wire fence machine, a plurality of simultaneously operated twisting devices adapted to twist strands of wire together between the pickets of the fence fabric, a plurality of feed-drums adapted to engage the several pickets of the fence fabric as it leaves the twisting devices, a train of gears for operating said feed-drums including a worm gear mounted on the shaft of one of the feed-drums, a worm driving gear in mesh with said worm gear, a bundling drum, means for driving said bundling drum at a relatively decreasing speed as the diameter of the fabric wound thereon increases, said means comprising a frictional disc actuated by a frictional driving disc on one of the feed-drums, a partially screw threaded shaft journaled on which the frictional driven disc is mounted, a gear on said last named shaft in mesh with a gear on the shaft of the bundling drum, a traveling yoke tapped to receive the thread-

ed shaft and adapted to engage the hub of the frictional driven disc, whereby the frictional driven disc may be shifted toward the periphery of the frictional driving disc as the diameter of the fence fabric increases upon the bundling drum and means for releasing said traveling yoke that it may be returned to its initial position upon removing the roll of fence fabric from the bundling drum.

14. In a wire fence machine, a plurality of twisting members adapted to twist wire strands together to form the lateral cables of a fence, means for feeding wire pickets between the strands of the lateral cables, means for looping the ends of the pickets including spaced perforated platforms, on which the ends of the pickets may be bent on the arc of a circle, a vertically movable platen above each platform, each provided with a plurality of downwardly directed pins of different length adapted to successively act upon the ends of the wire pickets to bend the ends of the wire pickets upon the arc of a circle on said platforms, means for actuating the platens to cause the pins thereof to engage the ends of the pickets, and means for withdrawing the platens from cooperative relation with the platforms.

15. In a wire fence machine, a plurality of simultaneously operated twisting devices adapted to twist strands of wire together between the pickets of the fence fabric as it leaves the twisting devices, a train of gears for operating said feed drums including a worm gear mounted on the shaft of one of the feed drums, a worm driving gear in mesh with said worm gear, a bundling drum, means for driving said bundling drum at a relatively decreasing speed as the diameter of the fabric wound thereon increases, said means comprising a frictional disk actuated by a frictional driving disk on one of the said feed drums, a partially screw threaded shaft journaled in the machine on which the frictional driven disk is mounted, an operative connection between said shaft and the bundling drum shaft, a travelling device tapped to receive the threaded shaft and adapted to engage the hub of the frictional driven disk, whereby the frictional driven disk may be shifted toward the periphery of the frictional driving disk as the diameter of the fence fabric increases upon the bundling drum.

16. In a wire fence machine, a frame, a plurality of twisting members adapted to twist wire strands together to form the lateral cables of a fence, each including a transverse hole and slot at one end for the passage of the pickets of the fence, means for rotating the twisting members, a rock shaft mounted in the frame above said ro-

- tating means, a plurality of arms depending from and keyed to said rock shaft, a swinging jaw pivoted to the free end of each of the rocking arms, a shaft journaled in the frame adjacent the rock shaft, a link pivoted to each of the swinging jaws and to the second mentioned shaft whereby the swinging jaws may be automatically closed to guide the picket and afterwards opened to release the picket simultaneously with the operation of the rock shaft and a consequent swinging of said arms, and means for actuating the rock shaft.
17. In a wire fence machine a frame, a plurality of twisting members adapted to twist wire strands together to form the lateral cables of a fence, each including a transverse hole and slot at one end for the passage of the pickets of the fence, means for rotating the twisting members, a rock shaft mounted in the frame above said rotating means, a plurality of arms depending from and keyed to said rock shaft, a swinging jaw pivoted to the free end of each of the rocking arms, a shaft journaled in the frame adjacent the rock shaft, a link pivoted to each of the swinging jaws and to the second mentioned shaft whereby the swinging jaws may be automatically closed to guide the picket and afterwards opened to release the picket simultaneously with the operation of the rock shaft and a consequent swinging of said arms, means for actuating the rock shaft, and means for looping the ends of the pickets and connecting them with the wire fabric to provide finished edges for the fabric.
18. In a wire fence machine, a frame, a plurality of twisting members adapted to twist wire strands together to form the lateral cables of a fence, each including a transverse hole and slot at one end for the passage of the pickets of the fence, means for rotating the twisting members, a rock shaft mounted in the frame above said rotating means, a plurality of arms depending from and keyed to said rock shaft, a swinging jaw pivoted to the free end of each of the rocking arms, a shaft journaled in the frame adjacent the rock shaft, a link pivoted to each of the swinging jaws
- 5 and to the second mentioned shaft whereby the swinging jaws may be automatically closed to guide the picket and afterwards opened to release the picket simultaneously with the operation of the rock shaft and a consequent swinging of said arms, means for actuating the rock shaft, and automatically operable, coercive devices to bend the ends of the pickets at one side of the fence fabric to loop the pickets and thereby provide for a finished edge for the fence fabric.
19. In a wire fence machine, a plurality of wire spools, a plurality of twisting members adapted to twist wire strands delivered in pairs from the spools to the twisting members, a trough mounted on the frame to guide a single picket transversely to the line of feed of the strands of wire, feed rolls through which each picket passes to position with relation to the lateral strands of wire and a device mounted on the trough for engagement with the outer ends of the respective picket to force the same between the feed rollers into cooperative relation with the twisted lateral strands.
20. In a wire fence machine, a plurality of wire spools, a plurality of twisting members adapted to twist wire strands delivered in pairs from the spools to the twisting members, a trough mounted on the frame to guide a single picket transversely to the line of feed of the strands of wire, feed rolls through which each picket passes to position with relation to the lateral strands of wire and a device mounted on the trough for engagement with the outer ends of the respective picket to force the same between the feed rollers into cooperative relation with the twisted lateral strands, means including a plurality of feed drums to feed the finished fabric forwardly as the latter leaves the twisting means and means for bundling the wire fabric upon leaving the feed drums.

In testimony whereof, I sign this specification in the presence of two witnesses.

JOHN S. BARNES.
